CLAIM

We claim the ornamental design for a garment, as shown and described.

DESCRIPTION

FIG. 1 is a front perspective view of a garment, such as a softshell jacket.

FIG. 2 is a rear perspective view of the garment shown in FIG. 1.

FIG. 3 is a front view of the garment shown in FIG. 1.

FIG. 4 is a rear view of the garment shown in FIG. 1.

FIG. 5 is a right side view of the garment shown in FIG. 1; and,

FIG. 6 is a left side view of the garment shown in FIG. 1. The interior of the garment forms no part of the claimed design. The broken lines at the neck and sleeve openings represent the boundary of the claimed design adjacent the unclaimed interior and form no part of the claimed design. The broken lines on the interior of the garment form no part of the claimed design. The broken lines depicting the zipper pulls and the hang-tab form no part of the claimed design. The remaining broken lines on the outer surface of the garment represent stitching and are part of the claimed design.
